Hanson M. Howard

UNITED STATES PATENT OFFICE.

ELMER R. POPE, OF HAMILTON, MASSACHUSETTS, ASSIGNOR TO UNITED SHOE MANUFACTURING CORPORATION, OF PATERSON, NEW JERSEY, A CORPORATION OF NEW JERSEY.

HEEL HOLDER.

Application filed March 9, 1925. Serial No. 14,178.

This invention relates to heel holders and is herein shown as embodied in a heel attaching machine holder for locating and maintaining a heel in position to be attached 5 to a shoe.

The object of the invention is to improve the construction of heel holders, with a view to increasing the accuracy of the location of the heel or heel parts, the range and 10 variety of work which can be handled and the ease and speed with which the holder may be manipulated.

The illustrative device herein shown is particularly designed to deal with two-part 15 heels, one example of which is a heel comprising a rigid base section and a rubber top section, commonly called a rubber heel. The utility of the invention, however, is not limited to two-part heels, inasmuch as it 20 will be apparent to those skilled in the art that some of its features are equally applicable to a holder for unitary heel or a single heel section.

In the illustrated embodiment of the invention provision is made for holding a heel base and an unattached, normally curved, deformable heel such, for example, as a concavo-convex rubber heel in proper register with each other while the base is moved 30 toward the deformable heel to flatten the latter under the influence of pressure applied through the base. This is accomplished by providing a ring for holding the deformable heel, in combination with a base 35 holder spaced from the ring and having a normally fixed rear gage and breast engaging members or gages, said members or gages being yieldingly movable in the direction of their height in order that the required approaching movement of the heel parts may be effected without releasing 40 either of the heel parts from the holder until the attachment of the heel to the shoe is complete. This feature of the invention is of general utility in holders for heels or heel sections where any substantial yielding, in a heightwise direction, is liable to occur while a heel or heel section is being operated upon. Two independently movable breast gages are preferably employed, in order that they may readily accommodate 45 themselves to the final position of the heel part when it is in position to be operated

upon, and heightwise movement of the gages is provided for by mounting them for pivotal 55 movement about horizontal axes, the gages themselves, as herein shown, being in the form of forked breast corner engaging members movable toward and from each other in right lines and also toward and 60 from a forked rear gage which is normally fixed in position.

When the invention is embodied in a holder for separate rubber heels and bases the holder preferably comprises two subsidiary holders, one of which is a permanent holder adjustable to bases of different sizes, and the other of which is an interchangeable, non-adjustable holder, such, for example, as a ring having an opening to fit 70 a rubber heel. In this connection a feature of the invention which contributes to the ease and speed with which the holder may be changed to accommodate heels of different sizes consists in the provision of engaging elements upon the two subsidiary 75 holders, which elements co-operate automatically to adjust the permanent holder in accordance with the size of any individual, interchangeable holder or ring 80 when the latter is placed in operative position. The operator is thus relieved from the necessity of paying any attention to the adjustment of the permanent holder, having only to select the proper ring 85 for the work in hand and place it in its proper position in the machine. The elements of the interchangeable holder or ring which effect the adjustment of the permanent holder may conveniently consist of eccentrically mounted projections engaging carriers upon which the breast corner engaging members constituting the breast gage of the permanent holder are mounted. The eccentric mounting of the projections makes 95 possible a certain amount of adjustment in their positions, whereby the approaching movements of the said gages may be independently and variably limited.

Other features and details of the invention and advantages to be derived from its use will be understood and appreciated from reading the following detailed description of one embodiment thereof in connection with the accompanying drawings, 100 in which

Figure 1 is an inverted plan view of the under side of the nailing die of a heelng machine with the heel holder attached;

Fig. 2 is a front elevation of the same;

Fig. 3 is a section on the line 3—3 of Fig. 1; and

Fig. 4 is a section on the line 4—4 of Fig. 1.

In the drawings, 10 may be considered as indicating the nailing die of a heelng machine of common and well known construction. To the under side of the nailing die 10 are secured parallel guides 12 which serve as supports for an interchangeable, non-adjustable ring or holder 14, provided with an opening 16 to fit the rubber heel 18 when the latter is flattened. The rubber heel 18, as shown in Fig. 3, is of the concavo-convex type and, when in its normal, undeformed, condition, does not exactly fit the opening 16.

A stationary bracket 20 is mounted upon the back of the nailing die 10 and supports a forked rear gage 22 which lies beneath the ring 14. The rear gage 22 may be adjusted forwardly or rearwardly with respect to the nailing die and the ring by an adjusting screw 24 threaded into the bracket 20 and the gage may be secured in adjusted position by a clamping bolt 26 passing through a slot 28 in the bracket. The forked rear gage 22 is thus normally stationary but may be adjusted to accommodate bases or heel sections of different sizes or shapes. 30 indicates a heel base which is held in engagement with the rear gage 22 by two forked, breast corner engaging members or gages 32 which, with their mountings and operating mechanism, are alike. Only one of them, therefore, will be described in detail.

Each of the forked members 32 has an enlarged hub 34 which is bored out to fit loosely over a round rod 36. The rod 36 is slidably mounted in a carrier 38 and is prevented from rotating therein by a pin 40, secured in the rod and sliding in a slot 42 in the carrier. A compression spring 44, surrounding the rod 36 and bearing against the rear of the carrier, tends to move the rod and the forked gage 32 rearward.

The carrier 38, by virtue of a dove-tailed support 46, is bodily movable in right lines transverse to the longitudinal axis of the heel holder. A compression spring 48 tends to move the carrier inwardly of the holder and, inasmuch as the two carriers 38 and their associated gages 32 face each other, the two springs 48 yieldingly effect approaching movement of the gages 32.

A pin 50 threaded into the hub 34 extends radially into a segmental opening 52 formed in the rod 36, the walls of the opening being so disposed that the hub 34 is prevented from longitudinal movement in relation to the rod 36 but is allowed a limited amount of rotative movement about the horizontal

axis of the rod. The arrangement is such that the gages 32 will normally be substantially horizontal, as shown in Fig. 2, but are easily movable upwardly, in directions normal to their own planes, toward the ring 14. 70 It will be observed that the gages 32 thus have a possibility of movement in three directions namely, two directions at right angles to each other in the planes of the gages and a third direction normal to their planes. It will furthermore be apparent that the springs 44 and 48 constitute yielding means for moving the breast corner engaging members 32 toward each other and toward the rear gage 22, in order securely 80 to hold and accurately to locate the heel base 30.

To facilitate the introduction of the heel base into the holder it is desirable that the breast corner gages 32 be not very much 85 closer together than the width of the heel base at the points where its sides are to be engaged by the gages. Provision is made for maintaining an adjustably predetermined separation between the gages 32, and the means herein illustrated for accomplishing this result consists of pins 54 eccentrically mounted on short bolts 56 which are secured in the ring 14 by nuts 58. The inwardly facing surfaces 60 of the carriers 95 38 are so formed that when the ring 14 is pushed into place from the front of the machine the pins 54 will engage said surfaces 60 and effect the proper separation of the carriers 38 and consequently of the 100 breast corner gages 32. The bolts 56 will be so located in each heel ring 14 that the spacing between the gages 32 will be substantially correct for a heel base to be used with a heel which will fit the opening in 105 that ring. Small adjustments or variations of this spacing may be secured by loosening the nuts 58 and turning the bolts 56 about their axes until the gage spacing pins 54 are positioned as desired and it will be observed that it is possible thus variably to 110 limit the approaching movements of each of the members 32 independently of the other.

In dealing with heel bases, or indeed any heels or heel sections which are thicker at 115 the rear than at the breast, it is desirable that the rear gage 22 which, in the present instance is normally stationary, should be thicker or higher than the breast gages 32, which are made thin enough not to interfere with the application of the heel attaching pressure when the heel 18 is flattened and the base 30 pressed against it. The rear gage 22 is high enough to maintain a secure hold upon the heel base when the parts are in the position shown in Fig. 3 but is not thicker than the rear edge of the heel base and consequently does not interfere with the application of the heel attaching pressure. 125 130

In the use of the illustrated device the rubber heel is inserted in the ring 14 which constitutes its holder, and the base is inserted between the holding members or gages 32 and 22 which constitute its holder. By reason of the spring actuation of the gages 32 toward each other and toward the rear gage 22 the heel base is held securely, and effectively prevents the heel 18 from dropping out of the ring 14 in case the heel does not fit the opening 16 sufficiently closely to be sustained securely. The shoe to which the two-part heel is to be attached is jacked up against the under side of the base 30 in the usual and well known manner, the heel 18 being flattened by pressure exerted upon it through the base 30. The pivotal mounting of the breast corner gages 32 permits them to yield upwardly as the base 30 moves upwardly under the influence of the pressure applied to it, while the relatively thick rear end of the base moves up into the stationary rear gage 22. The two heel parts are thus positively and accurately located and held while the attaching nails are driven in the usual manner.

Having described the invention, what is claimed as new and desired to be secured by Letters Patent is:

- 30 1. A holder for a heel base and a normally curved, deformable heel, comprising a ring having an opening to fit the heel when flattened, and a base holder spaced from the ring sufficiently to accommodate in the ring
- 35 a heel in its normal, curved condition, said base holder having a normally fixed rear gage and breast engaging members which are yieldingly movable toward the ring to permit a base in said base holder to move toward the ring to flatten the heel under the influence of pressure applied through the base.
- 40 2. A heel holder having a normally fixed rear gage and a breast gage comprising a plurality of breast engaging members which are independently movable heightwise.
- 45 3. In a heel holder, the combination of

a forked rear gage and a plurality of forked breast corner engaging members, said members being movable in their own planes 50 toward the rear gage and also movable in directions normal to their own planes.

4. In a heel holder, the combination of a rear gage and a plurality of breast engaging members, said members being movable in right lines at angles to each other in their own planes and also movable in directions normal to their own planes.

5. In a heel holder, a plurality of breast corner engaging members movable horizontally 60 in right lines toward each other and pivotally movable vertically about horizontal axes.

6. In a heel holder, the combination of a plurality of heel engaging members normally operatively movable toward and from each other and means for independently and variably limiting the approaching movements of each of said members.

7. A holder for two-part heels, comprising a permanent holder for one heel part which permanent holder is adjustable to heel parts of different sizes, and a readily interchangeable, non-adjustable holder for the other heel part, said permanent and interchangeable holders having engaging elements which co-operate automatically to adjust the permanent holder to correspond to the size of any individual interchangeable holder when the latter is placed in operative 75 position.

8. A holder for a heel base and a rubber heel, comprising a permanent base holder adjustable to bases of different sizes, and an interchangeable, non-adjustable heel ring, 80 normally in register with each other, said ring having projections arranged to engage elements of the base holder, automatically to adjust the base holder in accordance with the size of the ring when the ring is placed 85 in operative position.

In testimony whereof I have signed my name to this specification.

ELMER R. POPE.
